TOOTH BRUSH

William H. Doyle, White Plains, N. Y.

Application July 3, 1935, Serial No. 29,703

3 Claims. (Cl. 15—188)

This invention relates to tooth brushes and is herein disclosed as embodied in a structure having a metal or celluloid or other stiff handle and a rubber brush head or cleaning surface.

5 The ordinary bristle tooth brush, if properly designed, is a fairly effective cleaner of teeth when new and sterile, but after being used once it becomes a breeding place for germs. Moreover, after considerable use it becomes soft, 10 bristles often wear short, others fall out, and the brush is both inefficient and unhygienic.

The bristle tooth brush is too costly to throw away after being used only once, is almost always slightly irregular when new, and sometimes sheds 15 bristles at first, so that it is more agreeable to clean the teeth with a slightly worn tooth brush, even though more unhygienic.

According to the present invention these and other objections are overcome by building a brush 20 out of a handle and a detachable head having a continuous elastic body and a head which may be rubber faced, the facing being preferably provided with flexible fins and being so low in cost that the facing may economically be used only 25 once and then thrown away, with the result that a hygienic or sterile head is always available at trivial cost.

Moreover, the fins may be so formed that they 30 tend to hold dentifrice at their bases so that the dentifrice is effectively positioned for tooth cleaning.

The head may take any of several forms, and the handle may also take any of several forms, 35 one form holding the head by mere friction and grip of the elastic rubber, another form holding the head by a clamp, preferably so formed that no damp part can separate from the body part while the brush is usable.

Other features and advantages will hereinafter 40 appear.

In the accompanying drawings,

Figure 1 shows one form of brush including a separable handle and head.

45 Figure 2 is a large scale end view of Figure 1.

Figure 3 is a section on the line 3—3 of Figure 2.

Figure 4 is a section on the line 4—4 of Figure 3.

50 Figure 5 is a view of an extruded tube for forming a series of head facings of one form.

Figure 5a is a view of a single head facing.

Figure 6 is an end view of another form of brush.

55 Figure 7 is a view of another form of cleaning member.

Figure 8 is a view of an extruded half-rod for forming a series of heads like that of Figure 5.

Figure 9 is an end view of still another form of brush head.

Figure 10 is a section on the line 11—11 of 5 Figure 9.

Figure 11 is a view of a holding member.

Figure 12 is a view of the head end of the handle for the head of Figure 9.

Figure 13 is an end view of another form of 10 brush head.

Figure 14 is a section on the line 15—15 of Figure 13.

Figure 15 is a view of the handle head.

Figure 16 is a view of the head to fit on the 15 handle head of Figure 15.

Figure 17 is an end view of a brush head of another form.

Figure 18 is a section on the line 19—19 of Figure 17.

Figure 19 is a view of the handle head of Figure 17.

The brush of Figure 1, includes a handle 21 to be grasped, a head 26, a rubber facing 22 for the latter, including axial pointed fins 23 and axial 25 rounded risers 24, the facing 22 being in the form of a ring or belt lying in a flat depression 25 in the handle head or end post 26.

In the form shown the head 26 of the handle is 30 approximately half round with a diameter of one-half inch cut away one-sixteenth deep to make the depression 25 on the round front 27 and cut away on the nearly flat back 28 to one-eighth inch deep.

The end 29 of the handle is rounded smoothly 35 off, turning to a sharp curve at the corner 30 to facilitate the pushing of the elastic rubber head 22 over the end 29 until it seats itself in the depression 25.

The elastic facing 22 is preferably annular and 40 about five-eighths of an inch in diameter from the top of one rounded riser 24 to the top of the opposite riser 24, with a central opening about three-eighths of an inch in diameter. The fins 45 or flappers 23 are shown separated by a cut one thirty-second of an inch deep from the round risers 24, and rise about one thirty-second of an inch above the tops of the risers 24.

The depression 25 in which rubber facing fits 50 is shown as slightly over one-fourth inch long axially of the handle.

The end walls of the depression are shown as about one-sixteenth inch thick. The facing 22 fits closely in the depression 25, projecting well 55 above the end walls on the rounded or cylindrical

face, to about double the free height of fin, but only the tops of the fins project above the end walls on the flat back 28.

Thus as the brush is held in the hand and 5 rotated back and forth on its axis, the fins 23 sweep over the teeth bending to and from the risers 24 and squeezing out from between them any dentifrice which has been applied to the head.

In the form shown, which is well adapted for 10 extrusion, the head facing carries sixteen fins 23 and sixteen risers 24.

The head and brush shown in Figure 6 include a handle 21 and brush head 31, having long fins 23 and short or half-height fins 24^a, but held to 15 the handle by a threaded clamp head or end wall 32 screwing into a threaded socket 33 in the flat end 34 of the handle 21.

The brush head 31, as more clearly seen in the view of the extruded half rod blank of Figure 9, 20 is shown as having a flat back 35 and a three thirty-second inch opening 36 through which the threaded shank 37 of the clamp head 32 passes with a close fit, and nearly centrally of the elastic rubber.

25 Instead, one of the other heads, a head having a periphery like that shown in Figure 7, may be used having fins 44 which spring from undercut bases 45 so that the pockets formed by the relatively flat tops 46 may hold dentifrice, and may 30 be limber and flexible enough to function as brush ends one-sixteenth inch long.

The brush head 47 shown in Figure 10 is adapted to fit closely over the slightly tapering triangular post 48 of the handle 21 of Figure 12, 35 for this purpose being provided with a triangular opening 49 very slightly smaller than the post 48. To hold the ends of the head 47 of the elastic rubber, the post 48 is of sufficient length to pass through both the upstanding ends 50 of a supporting frame 51, adapted to closely fit the ends of the head 47, and provided with triangular openings 52, 53 in the ends 50 fitting closely over the post 48.

The head 54 shown in Figure 14, like the head 45 47, may have the surface shown in Figure 8, and is shown as provided with an opening 55 in its back which broadens to a wide cavity 56 (about three sixteenths deep) so as to be sprung over the deeply undercut post 57 projecting from 50 the handle 21 and lying upon a flat floor 58 which supports the flanges 59 of the elastic rubber on each side of the opening 55. To hold the ends of

the head 54, there are provided semicircular walls 60 at each end of the post 57, rising from the floor 58 to closely fit the head. The floor is shown as three-fourths of an inch wide, exactly 5 the width of the head, but the one-sixteenth inch walls terminate about one-eighth inch short of the sides of the floor.

The brush head shown in Figure 18 may be identical with the head 54 of Figure 14, but it 10 abuts against a flat end 61 of the handle 21, somewhat smaller than the solid end of the head, and is held on the triangular post 62 by a rotatable end 63 of the post. In the form shown the end 63 may be turned on its pivot 64, so that its flat sides 65 lie exactly in line with the flat sides of 15 the triangular post 62.

Thus the head 54 slips easily over the post 62 in the position of Figure 19, but is held on the post when the end 63 is rotated on its pivot 64. Apparently, the most satisfactory rubber composition 20 for the heads is one carrying 43% or more of gum rubber, and, in the form shown, the heads are formed by extruding the rubber composition through dies which form the fins and risers longitudinally of the tube or rod or half rod as it 25 issues.

The extruded rod or tube is then cut into suitable lengths, thus the whole process eliminates many of the difficulties and expenses of molding 30 separate heads.

Having thus described certain embodiments of the invention, what is claimed is:

1. A brush head comprising a body the front face of which is substantially in the form of a segment of a cylinder and the rear face of which is substantially flat, and a rubber facing detachably mounted on said body and having flexible fins throughout at least a portion of its periphery and disposed longitudinally of the facing. 35

2. A brush head having a facing of a continuous flexible body provided throughout at least a portion of its periphery with fins extending longitudinally of the body and projections intermediate the fins of less depth than said fins and also extending longitudinally of the body. 40

3. The combination of a holder having end walls with triangular apertures, a handle, having a triangular end, for said holder, and a detachable and replaceable facing of resilient material inserted in the holder upon said handle and confined between end walls of said holder. 45

WILLIAM H. DOYLE.
